US00D915824S

(12) **United States Design Patent** (10) **Patent No.:** **US D915,824 S**
Bennion et al. (45) **Date of Patent:** **** Apr. 13, 2021**

(54) **COOKING APPARATUS**

- (71) Applicant: **Weber-Stephen Products LLC**, Palatine, IL (US)
- (72) Inventors: **Derek Bennion**, Chicago, IL (US); **Qian Hamel**, Evanston, IL (US); **Carmen O. Lira-Nunez**, Downers Grove, IL (US)
- (73) Assignee: **WEBER-STEPHEN PRODUCTS LLC**, Palatine, IL (US)
- (**) Term: **15 Years**
- (21) Appl. No.: **29/701,956**
- (22) Filed: **Aug. 15, 2019**

Related U.S. Application Data

- (63) Continuation of application No. 29/694,202, filed on Jun. 7, 2019.
- (51) **LOC (13) Cl.** **07-02**

(57) **CLAIM**

The ornamental design for a “cooking apparatus”, as shown and described.

DESCRIPTION

FIG. 1 is a front right perspective view of a cooking apparatus.

FIG. 2 is a front left perspective view of the cooking apparatus of FIG. 1.

FIG. 3 is a rear perspective view of the cooking apparatus of FIG. 1.

FIG. 4 is a front view of the cooking apparatus of FIG. 1.

FIG. 5 is a rear view of the cooking apparatus of FIG. 1.

FIG. 6 is a left side view of the cooking apparatus of FIG. 1.

FIG. 7 is right side view of the cooking apparatus of FIG. 1.

FIG. 8 is a top view of the cooking apparatus of FIG. 1.

FIG. 9 is a bottom view of the cooking apparatus of FIG. 1; and,

FIG. 10 is an enlarged, rear perspective view of the cooking apparatus of FIG. 1.

The features shown in even broken lines form no part of the claimed design. The features shown in dot-dashed broken lines indicate boundaries of the claimed design and form no part thereof.

1 Claim, 10 Drawing Sheets
